(57) **CLAIM**

The ornamental design for an indwelling needle, as shown and described.

DESCRIPTION

FIG. 1 is a perspective view of an indwelling needle;
FIG. 2 is a front view thereof;
FIG. 3 is a rear view thereof;
FIG. 4 is an enlarged left side view thereof;
FIG. 5 is an enlarged right side view thereof;
FIG. 6 is a top view thereof;
FIG. 7 is a bottom view thereof;
FIG. 8 is an enlarged front view of wing part thereof;
FIG. 9 is an enlarged rear view of wing part thereof;
FIG. 10 is an enlarged top view of wing part thereof; and,
FIG. 11 is an enlarged bottom view of wing part thereof.
The portion shown by broken lines is for illustrative purposes only and forms no part of the claimed design.
